UNITED STATES PATENT OFFICE.

LEE S. CHADWICK, OF SHAKER HEIGHTS VILLAGE, OHIO, ASSIGNOR TO THE CLEVELAND METAL PRODUCTS COMPANY, OF CLEVELAND, OHIO, A CORPORATION OF OHIO.

STOVE.

Application filed February 25, 1922. Serial No. 539,079.

To all whom it may concern:

Be it known that I, LEE S. CHADWICK, a citizen of the United States, residing at Shaker Heights Village, in the county of 5 Cuyahoga and State of Ohio, have invented a certain new and useful Improvement in Stoves, of which the following is a full, clear, and exact description, reference being had to the accompanying drawings.

10 This invention relates to improvements in the class of burners disclosed and claimed in an application filed by me on the 26th day of February, 1921, and bearing Serial No. 448,111.

15 The burner which constitutes the subject matter of said application is so constructed that the drum or flue may be readily lifted from the combustion device to give unobstructed access to the wick for the purpose 20 of cleaning or replacing it; or the drum may be tilted with respect to the burner for the purpose of lighting the wick. Also, the drum or flue shown in said application has a double wall, the inner wall in the preferred form extending from the top about 25 halfway down the outer wall where it joins said outer wall immediately below air inlet openings, thereby to enclose a space through which a so-called auxiliary current of air 30 may rise. Also, provision is made for admitting fresh air to the lower end of the drum and deflecting it into close proximity to the wall thereof. This arrangement prevents undue heating of the drum and at the 35 same time increases the efficiency of the burner by adding to the quantity of hot air which would ordinarily issue from the top of the drum the auxiliary current of air which has during its course of travel through the 40 space between the inner and outer walls become heated by radiation from the inner wall.

45 My present construction possesses all the foregoing features and affords the same advantages as my former construction over the common types of drum burners wherein, as stated in said application, there is a considerable waste of heat and an undue heating of the drum, especially in the region of its 50 upper end.

55 Objects peculiar to my present invention are the provision of a burner of the aforesaid class wherein the drum may be very readily lifted from the burner and with equal ease re-placed thereon but which, when

placed upon the burner, assumes a positive hinge connection therewith so that the drum may be swung back and entirely out of the way to expose the upper end of the burner, enabling the wick to be readily cleaned or 60 removed, the hinge connection incorporating a stop for limiting the swinging movement of the drum; the provision of a rest for the drum when tilted rearwardly, which rest yields under the weight of the drum and relieves it of the shock which would otherwise be imposed upon it and which would be liable to crack the enamel wherewith drums of this character are usually coated; the provision of a support for the drum when in 65 normal vertical position, which is independent of the hinge connection between the drum and combustion device, thereby insuring correct relationship between these two units which is exceedingly important in 70 burners of this character as the slightest departure therefrom will disturb the drafts and produce an irregular flame of low efficiency; the provision, in a stove incorporating drum burners of different diameters 75 but of the same height and arranged in transverse alignment, a variable hinge connection between the larger drum and its combustion device enabling it to swing within the same vertical space as the smaller 80 drum; and to provide, in such variable hinge connection, means for maintaining the relatively movable parts in a definite relation to each other during the swinging movement.

85 The foregoing objects, and others herein- 90 after appearing, are attained in the embodiment of the invention illustrated in the drawings accompanying and forming a part hereof and wherein Fig. 1 is a front elevation of a stove structure embodying my im- 95 provements; Figs. 2 and 3 are sections on the respective lines 2-2 and 3-3 of Fig. 1, showing the large and small burners, re- 100 spectively; Fig. 4 is a central vertical section from front to rear through the drum supporting collar burner band that are incor- 105 porated in the larger burner; Fig. 5 is a plan of what is shown in Fig. 4, with parts broken away to more clearly reveal certain structural details; Figs. 6 and 7 are more or 110 less diagrammatic sectional views of the hinge connection between the drum supporting collar and burner band that are illustrated in Figs. 4 and 5, Fig. 6 showing the parts in normal position, while Fig. 7 illus-

trates them in the position assumed upon the tilting of the drum; Fig. 8 is an enlarged central vertical section through the smaller drum and its supporting collar, the burner band being shown in elevation; Figs. 9 and 10 are views, similar to Figs. 4 and 5, of the drum supporting collar and burner band of the smaller burner, Fig. 9 indicating in dotted lines the manner of applying the drum to the collar; and Figs. 11 and 12 are sectional details on the lines 11-11 and 12-12, respectively, of Fig. 10.

The frame structure of the stove comprises a top 1 that is supported a suitable distance above a base 2 by end panels 3 and a back wall 4, the base, in turn, being sustained a proper distance above the floor by legs 5. A fuel supply pipe 10 is supported by and between the end panels 3 a comparatively short distance above the base 2, and beyond one of the end panels the supply pipe has the usual connection with a fuel reservoir (not shown). Burners 12 and 13 are partly supported by, and have communicative connection with, the supply pipe through elbow fittings 14 that are secured to the supply pipe by suitable clamps 15, and further, by the base 2, through legs 16. The burners are arranged in axial alignment with openings 17 in the stove top, the openings being surrounded by depending flanges 18.

The burner 13 is of the customary size, while the burner 12 is made considerably larger to adapt it to certain purposes heretofore incapable of attainment in stoves of this character. This burner produces an intense heat in a very short time as compared with the smaller burner.

Associated with the respective burners 12 and 13 are the drums or flues 20 and 21 of appropriate size. Each drum is provided with a window 22 of mica or other suitable transparent material, and with a handle 23.

It is essential that the drums be capable of ready removal from the burners for the purpose of lighting, cleaning or removing the wicks; and it is desirable to so mount them that they may be conveniently lifted from and replaced upon the burners, or tilted with respect thereto so as to expose the wick for cleaning, lighting and replacement purposes, and to this end my invention provides a drum supporting collar that is hingedly connected to the burner and wherewith the drum has a readily separable connection, such connection serving to retain the drum on the collar during the tilting operation while permitting the drum to be easily and naturally lifted from the collar when the collar is in normal position.

It may also be explained that in burners of this character it is necessary to have the drums or flues very accurately positioned with respect to the burners in order to

properly balance the drafts, so to speak, and produce a clean, odorless, and efficient flame. To this end, I provide means for supporting the collar, and, through it, the drum, from the burner independently of the hinge connection between the collar and burner, realizing that probable irregularities in the hinge connection would result in an improper relation between the drum and burner, such provision avoiding also the accuracy in the making of the hinge parts and connections which would otherwise be required, thus saving time and labor.

To the attainment of the greatest efficiency, the tops of the drums must be a certain distance below the lower edges of the flanges 18 that surround the openings 17 and below which the drums are situated. It happens that under this arrangement the small drum may swing clear of the flange 18 on a hinge center located to the rear of the upper end of the burner, while with the larger drum 20 it is necessary to provide a variable hinge connection between the supporting collar which carries the drum and the larger burner wherewith it is associated. I shall first describe the hinge connection of the larger drum collar, with particular reference to Figs. 2, 4, 5, 6 and 7.

So far as they concern my present invention, the burners 12 and 13 are of the ordinary class of tubular burners, more detailed showings of which may be found in my Patents Nos. 1,246,878, 1,251,638, and 1,122,856.

A suitable distance below its upper end, the burner 12 (indicated in dotted lines in Fig. 4) is provided with a circumferential bead 25. A burner band 26 encircles the burner and has a shoulder 27 which rests upon the bead 25, and from the outer edge of the shoulder there depends a flange 28 that surrounds the bead and is notched at suitable circumferentially spaced points to provide tongues 29 which are clinched under the bead to hold the band against vertical displacement. Extending downwardly and rearwardly from each side of the band 26 is an arm 30, provided with a strengthening bead 31, and which is turned inwardly at its rear end to provide an abutment 32. At points spaced circumferentially of the band 26, lugs 35 and 36 are struck from the material of the band and turned radially outwardly, those designated 35 being situated toward the front of the burner, while those designated 36 are located toward the rear thereof. The upper edges of the lugs 35 and 36 are in a plane parallel with the top of the burner.

The drum supporting collar is designated generally by the reference numeral 40, and it is formed with a shoulder 41 which rests upon the lugs 35 and 36 and from the outer side of which a skirt 42 depends, the collar

being positioned properly with respect to the burner through the cooperation of said skirts with the outer ends of said lugs. Rising from the inner edge of the shoulder 41 and converging to within a comparatively short distance of the upper edge of the burner is a wall 43 which joins at its upper edge a gradually flaring deflector 44. Associated with the burner is the usual flame spreader 45 which serves, when the burner is in operation to direct the flame outwardly by virtue of air currents which it controls, and the flame, as it is supplied with air entering between the collar and the burner, follows the deflector 44 outwardly toward the wall of the drum 20 which is supported, through its inwardly directed flange 46, on the external ledge provided by the shoulder 41. The flange 46 has perforations 47 for the supply of additional air to the drum. Cooperation of the drum with the collar is identical in both burners, and, as illustrated in Fig. 9 (where the smaller burner is shown), the drum is adapted to be engaged over the collar with its bottom flange beneath a lug at the front of the collar. The lug beneath which the front portion of the drum flange is engaged is designated A in both burners, and by reason of its shape and the formation of the collar, the drum is caused to automatically assume a proper position on the collar with its flange beneath the lug by merely placing the drum over the collar.

Secured, as by spot welding or other suitable means, to the rear side of the skirt 42 of the collar 40 is the base of a hinge plate 50 which carries, at each end, an ear 51 having an arcuate slot 52 through which a hinge pintle 53 extends that is supported by and between the arms 30 of the burner band 26. Struck inwardly from the skirt 42 of the collar 40 are projections 55 which, when the collar is in normal position, are immediately forward of the lugs 36 of the burner band, the projections 55 being inclined downwardly and forwardly from the upper end of said lugs for a purpose which shall presently appear. The angle between the projections 55 and the shoulder 41 define fulcrum points whereon the collar is adapted to swing with respect to the burner band, the slots 52 of the ears 51, as well as the rear edges of said ears which engage the abutments 32 of arms 30, being formed on arcs which have the aforesaid fulcrum points as their centers. Therefore, during the initial rearward movement of the drum 20, it swings upon these fulcrum points until its upper end is clear of the flange 18 (note the arc whose radius is indicated by the arrow *a* in Fig. 2) and until the upper ends of the slots 50 engage the pintle 53. During the further rearward movement of the drum, the collar 40 swings on the pintle 53, the upper end of the drum describing an arc the radius of which is designated by the arrow *b* in Fig. 2. The rearward swinging movement of the collar is positively arrested by the engagement of stops 58, which project upwardly from the ears 51, with the abutments 32; while the drum comes to rest upon a yielding flange 56 that surrounds an opening 57 in the back wall 4 of the stove frame, provided for the accommodation of the drum when swung rearwardly. In this connection it may be explained that the burner drums are heavily coated with a vitreous enamel, and the shock absorbing quality of the yielding flange 56 protects the enamel from cracking. As will be more apparent from the diagrammatic sectional views of Figs. 6 and 7, the projections 55 are so inclined that they will escape the lugs 36 when the collar swings on the pintle 53; and the engagement of the curved rear edges of the ears 51 with the abutments 32 prevents the collar from sliding rearwardly on the hinge pintle when it approaches a position where-in the slots 52 are inclined upwardly and forwardly from the pintle.

I shall now describe the smaller burner, illustrated particularly in Figs. 3, 8, 9, 10, 11 and 12. To the upper end of the burner 13 is fitted a burner band 60 which has a shoulder 61 that rests upon a bead 62 of the burner. A flange 63 depends from the outer edge of the shoulder 61 and embraces the bead and is notched at points spaced circumferentially of the band to provide lugs 64 that are clinched beneath the bead 62 to hold the band securely in place. Immediately above the shoulder 61, as well as in the region of its upper end, the band 60 engages the burner, but intermediate these points it is enlarged somewhat. Within the rear side of this enlargement is confined the body portion of the burner hinge plate 66, and the ends of this plate are directed outwardly through slots 67 in the band and extend rearwardly from the burner in parallel relation to each other, the ends of the plate being formed into hook shaped ears 68 which carry a pintle 69. The upper edges of the plate 66, where the ends of the plate protrude through the slots 67, are in the same horizontal plane as the upper edges of lugs 70 which are struck radially outwardly from the band 60 toward the front side of the burner. A shoulder 72 of the drum supporting collar 73 bears upon the lugs 70 and upon the aforesaid portions of the plate 66 adjacent the band 60, which portions are designated 75 and are referred to hereinafter as collar supporting portions of the hinge plate. The design of the collar 73 is practically identical with that of the former collar 40, and it comprises the skirt 76 which depends from the outer edge of

the shoulder 72, and the upwardly converging wall 77 which rises from the inner edge of said shoulder and which, at its upper edge, merges into the flaring deflector 78. 5 The skirt 76, cooperating with the lugs 70 and the collar supporting portions 75 of the hinge plate 60 (as illustrated in detail in Figs. 11 and 12) insures proper alignment of the collar with respect to the burner. A 10 hinge plate 80 is applied to the inner rear side of the skirt 76 and terminates at its ends in parallel ears 81 which are extended through slots 82 in the skirt and lie along the inner sides of the upwardly directed 15 rear ends of aforesaid ears 68, the ears 81 having holes through which the pintle 69 extends but which holes are enough larger in diameter than said pintle to afford the collar 73 the freedom of movement necessary to insure its being supported by the lugs 70 and the collar supporting portion 75 entirely independently of the hinge. 20 Adjacent its center, the hinge plate 80 has a downwardly and rearwardly extending 25 tongue which constitutes a stop 83 that is arranged to engage the rear side of the burner and positively stop the collar, when the drum 21 is tilted rearwardly and rests upon the yielding flange 85 which surrounds 30 the opening 86 in the back wall 4 which is provided for the accommodation of this drum.

The physical characteristics of the drums 20 and 21 are identical and I shall proceed 25 to describe them in connection with the sectional view through the drum 21 as it is illustrated in Fig. 8. The drum comprises a cylindrical shell 90 which is provided at its upper end with an upwardly and inwardly 40 extending annular wall 91 that surrounds the outlet opening of the drum. An inwardly directed shoulder 92 is formed at about the vertical center of the drum by beading the shell inwardly throughout its 45 circumference, and resting upon the shoulder 92 is the outwardly flanged lower end of an inner wall 93 which has a converging upper end 94 disposed in close proximity to the aforesaid annular wall 91. Spacers 95 50 centralize the upper end of the inner wall within the shell 90 and by engagement with the wall 91 retain the flanged lower end of the wall against the shoulder 92. The shell 90 is provided with a series of air openings 55 96 immediately above the lower end of the inner wall. At its lower end, the shell 90 is provided with an inwardly directed base flange 97 which is adapted to rest upon the drum supporting ledge of the collar, and 60 said base flange is provided with a series of perforations 98.

The window 22, previously referred to, is provided by an opening 99 formed in the front side of the drum a suitable distance 65 above the top of the burner so that the flame

may be observed therethrough, and a pane 100 of transparent material, such as mica, is secured over the opening by a frame 101 attached to the drum as by means of a bolt 102, and a second bolt which also serves to 70 secure the handle 23 in place.

The drum herein disclosed functions practically the same as that shown in my former application above referred to. When the burner is in operation, a certain quantity of 75 air enters the space between the drum supporting collar and the burner and it, with the air which enters through the burner, under the control of the flame spreader, supplies the oxygen necessary to promote combustion. The burning gases follow the deflector which constitutes the upper terminal of the collar outwardly toward the wall of the drum and are picked up by the fresh air entering through the perforations 98 and 80 carried upwardly, the fresh air thus serving to protect the drum against the direct heat of the flame. However, by the time this air has reached the lower end of the inner wall 93, it has, by contact and intermingling 85 with the gases, acquired a very high temperature. The upper portion of the shell 90 is protected from this intense heat by the inner wall 93. The heat radiated by the inner wall creates an upward draft within 90 the space between said inner wall and the outer shell, and this draft is satisfied by fresh air entering through the openings 96. By the time the air which enters through the 95 opening 96 (hereinbefore referred to as the auxiliary current of air) reaches the top of the drum, it has been so raised in temperature as to materially increase the efficiency 100 of the burner by augmenting the main column of hot gases rising through the 105 drum.

Having thus described my invention, what I claim is:

1. In combination, a burner of the character set forth, a drum support permanently 110 hingedly connected to the burner, a drum resting upon the support and capable of being lifted therefrom, and means holding the drum against dislodgement from the support when the support is swung on its 115 hinge.

2. In combination, a burner of the character set forth, a drum support hingedly connected to the burner, a drum removably sustained by the support, the drum and support having parts which interengage and hold the drum against dislodgement from the support when the support is swung on its hinge. 120

3. In combination, a burner of the character set forth, a drum support hingedly connected to the burner at one side thereof, and a drum removably sustained by the support, the support having a lateral extension on its side opposite that whereon it has hinge con- 125

nection with the burner, and which extension overhangs a part of the drum thereby to hold the drum against dislodgement from the support when the support is swung on its hinge.

4. In combination, a burner of the character set forth, a drum support hingedly connected to the burner and having a stop which engages the burner to limit the swing¹⁰ movement of the support, and a drum resting upon the support and capable of being lifted therefrom, the drum and support having parts interengaging to hold the drum to the support when the latter is¹⁵ swung on its hinge.

5. In a stove structure, a burner of the character set forth, a drum support hingedly connected to the burner, a drum surmounting²⁰ the support, means limiting the swinging movement of the support, and a rest sustained by the stove structure in a position to receive and support the drum when tilted.

6. In a stove structure, a burner of the character set forth, a drum supported in²⁵ operative relation to the burner in such manner as to be capable of being tilted with respect thereto, said drum being coated with vitreous material, and a yielding rest incorporated in the stove structure and wherewith³⁰ the drum engages and whereby it is supported when tilted.

7. In a stove structure, a burner of the character set forth, a drum hingedly connected to the burner, said drum being coated³⁵ with vitreous material, the stove structure incorporating a wall having an opening through which the drum extends when swung on its hinge, the portion of the wall adjacent the lower edge of said opening sup-⁴⁰ porting the drum when tilted and so formed as to yield under the weight thereof.

8. In a stove structure, a burner of the character set forth, a drum hingedly connected thereto, said drum being coated with⁴⁵ vitreous material, the structure incorporating a wall which supports the drum when the latter is swung on its hinge, the edge portion of the wall wherewith the drum engages being formed so as to yield under the⁵⁰ weight thereof.

9. In combination, a burner of the character set forth, a drum, hinge connection between the drum and burner, and means for⁵⁵ sustaining the drum in operative relation to the burner independently of said hinge connection.

10. In combination, a burner of the character set forth, a drum, hinge connection between the drum and burner of such character as to permit the drum to shift its⁶⁰ position laterally with respect to the burner, and means for supporting and positioning the drum in operative relation to the burner independently of said hinge connection.

11. In combination, a burner of the character set forth, a drum support, hinge connections between the drum support and burner, a drum sustained by the support, and means supporting and positioning the drum⁷⁰ support and, through it, the drum, in operative relation to the burner.

12. In combination, a burner of the character set forth, a drum support, hinge connection between the support and burner of⁷⁵ such nature as will permit the support to shift its position with respect to the burner, a drum sustained by the support in a given relation thereto, and means supporting and positioning the support, and through it, the⁸⁰ drum in operative relation to the burner independently of the hinge connection.

13. In combination, a burner of the character set forth, a band applied thereto and having laterally extending lugs, a drum support, hinge connection between the drum support and band, the drum support having parts cooperating with the aforesaid lugs whereby the support is sustained and positioned in proper relation to the burner independently of said hinge connections, and⁸⁵ a drum surmounting the drum support.

14. In a stove structure, a burner, a drum supported in operative relation to the burner, the drum being arranged to tilt with respect to the burner, the structure being of⁹⁰ such nature as will afford only limited space within which the burner may tilt, the fulcrum point of the drum shifting during the tilting of the drum thereby to accommodate the movements of the drum to said limited space.

15. In combination, a burner, and a drum supported in operative relation thereto, the drum being arranged to tilt with respect to¹⁰⁵ the burner, the fulcrum point of the drum shifting during the tilting of the drum.

16. In combination, a burner, a drum supported in operative relation thereto, the drum being arranged to tilt with respect to the burner, and means whereby the fulcrum point of the drum is caused to shift during the tilting of the drum.

17. In combination, a burner, a drum supported in operative relation thereto, the drum being arranged to tilt with respect to the burner, and a plurality of fulcrum points whereon the drum swings successively during its tilting movement.

18. In combination, a burner having a¹²⁰ plurality of bearing parts constituting fulcrum axes, and a drum supported in operative relation to the burner and arranged to tilt with respect thereto, the drum swinging successively upon said axes during its tilt-¹²⁵ ing movement.

19. In combination, a burner, a drum support, a drum sustained by the support in operative relation to the burner, the drum and support being arranged to tilt with respect¹³⁰

to the burner, the fulcrum point of the support shifting during the tilting of the drum.

20. In combination, a burner, a drum support, and a drum sustained thereby in operative relation to the burner, the support and drum being arranged to tilt with respect to the burner, the burner having a plurality of bearing parts constituting fulcrum points whereon the support swings successively 10 during the tilting of the drum.

21. In combination, a burner having bearing parts, a drum, a drum support resting upon said bearing parts and sustaining the drum in operative relation to the burner, the 15 drum and support being arranged to tilt with respect to the burner, the support swinging upon a fulcrum defined by certain of said bearing parts during the initial tilting of the drum, and a pivot fixed 20 with respect to the burner and whereon the drum support swings during the remainder of its tilting movement.

22. In combination, a burner, a drum, a drum support sustaining the drum and hinge- 25 edly connected to the burner, and means sustaining the drum support independently of its hinge connection with the burner and so positioning it as to retain the drum in operative relation to the burner, said means 30 involving parts defining a fulcrum point whereon the drum support swings during the initial tilting of the drum, the support swinging upon its hinge during the remainder of the tilting movement of the drum.

35. 23. In combination, a burner, a drum supported in operative relation thereto and arranged to tilt with respect to the burner, the fulcrum point of the drum shifting during the tilting of the drum, and means for retaining the drum in given relation to the burner during its tilting movement.

24. In combination, a burner, a drum, a drum support sustaining the drum in operative relation to the burner, the drum and support 45 being arranged to tilt with respect to the burner, the fulcrum point of the support shifting during the tilting of the drum, and means for retaining the support in given relation to the burner during its swinging movement.

50. 25. In combination, a burner, a drum support, a drum separably connected to the support and sustained thereby in operative relation to the burner, the drum and support being arranged to tilt with respect to the burner, the fulcrum point of the support shifting during the tilting of the drum, and means for retaining the support in given relation to the burner during its swinging movement.

60. 26. In combination, a burner, a drum support, hinge connections between the drum support and burner, a drum sustained by the support, means sustaining the support 65 in a position to locate the drum in operative

relation to the burner, said means involving parts constituting a fulcrum point whereon the support swings prior to the coming into effect of its hinge connections with the burner whereby the drum, when tilted with respect to the burner, is caused to travel through a compound arcuate course.

70. 27. In combination, a burner having a hinge part, a drum support having a hinge part, a drum sustained by the drum support, the burner having bearing parts whereon the drum support rests and whereby it is positioned so as to locate the drum in operative relation to the burner, the drum and support being arranged to tilt with respect to the burner, certain of said bearing parts defining a fulcrum point whereon the support swings during the initial tilting movement of the drum, the hinge parts of the burner and support having one a pivot member and the other an arcuate slot through which the pivot member extends, the slot traveling along said member during said initial tilting movement of the drum and the support swinging upon said pivot member during the further tilting movement of the drum.

75. 28. In combination, a burner having a hinge part, a drum support having a hinge part, a drum sustained by the drum support, the burner having bearing parts whereon the drum support rests and whereby it is positioned so as to locate the drum in operative relation to the burner, the drum and support being arranged to tilt with respect to the burner, certain of said bearing parts defining a fulcrum point whereon the support swings during the initial tilting movement of the drum, the hinge parts of the burner and support having one a pivoted member and the other an arcuate slot through which the pivot member extends, the slot traveling along said member during said initial tilting movement of the drum, the support swinging upon said pivot member during the further tilting movement of the drum, said hinge parts involving cooperating portions which serve to retain the drum support in given relation to the burner during its swinging movement.

80. 100. 105. 110. 115. 120. 125. 130. 29. In combination, a burner having a hinge part, a drum support having a hinge part, a drum sustained by the drum support, the burner having bearing parts whereon the drum support rests and whereby it is positioned so as to locate the drum in operative relation to the burner, the drum and support being arranged to tilt with respect to the burner, certain of said bearing parts defining a fulcrum point whereon the support swings during the initial tilting movement of the drum, the hinge parts of the burner and support having one a pivoted member and the other an arcuate slot through which the pivot member extends, the slot traveling

along said member during said initial tilting movement of the drum, the support swinging upon said pivot member during the further tilting movement of the drum, 5 said hinged parts having respective stop portions which engage to limit the swinging movement of the support with respect to the burner.

30. In combination, a burner, a band applied thereto adjacent its upper end, the band having rearwardly extending hinge plates, a pintle supported by and between said hinge plates, the band also having outwardly projecting lugs, a drum support sustained by said lugs and incorporating hinge members projecting rearwardly alongside the hinge plates of the band, certain opposed ones of the aforesaid lugs defining a fulcrum axis, a drum sustained by the drum support in operative relation to the burner and arranged, with the support, to tilt with respect to the burner, the drum support swinging on said fulcrum axis during its initial tilting movement, the hinge members 25 of the support having arcuate slots through which the aforesaid pintle extends and which are described on a center coincident with the aforesaid fulcrum axis, the upper ends of the slots engaging the pintle at the 30 conclusion of the initial tilting movement of the drum whereupon the support swings upon said pintle, means restraining the support from shifting with respect to said fulcrum axis during the initial tilting movement of the drum, and means retaining the support in given relation to the burner during the remaining tilting movement of the drum.

31. In combination, a burner, a band applied thereto adjacent its upper end, the band having rearwardly extending hinge plates, a pintle supported by and between said hinge plates, the band having outwardly projecting lugs, a drum support sustained by said lugs and incorporating hinge members projecting rearwardly alongside the hinge plates of the band, certain opposed ones of the aforesaid lugs defining a fulcrum axis, a drum sustained by the drum support in operative relation to the burner and arranged, with the support, to tilt with respect to the burner, the drum support swinging on said fulcrum axis during its initial tilting movement, the hinged members of the support having arcuate slots through which the aforesaid pintle extends and which are described on a center coincident with the aforesaid fulcrum axis, the upper ends of the slots engaging the pintle at the conclusion of the initial tilting movement of the drum whereupon the support swings upon said pintle during further tilting movement of the drum, means restraining the support from shifting with respect to the said fulcrum axis during the initial tilting move-

ment of the drum, the hinge plates of the band having laterally extending lugs, and the hinge members of the drum support having curved parts described on the center of the upper ends of the aforesaid slots and engaging said lugs to retain the support in given relation to the burner during said tilting movement of the drum. 70

32. In combination, a burner, a band surrounding the burner adjacent its upper end, the band having outwardly extending lugs adjacent the front of the burner, a hinge member applied to the rear side of the band and having bearing parts in the plane of the aforesaid lugs, a drum support, a drum mounted upon the support, the aforesaid lugs and said bearing parts of the hinge member sustaining the drum support in a position to locate the drum in operative relation to the burner, a hinge member carried by the drum support, the hinge members of the band and support having one a pivot member and the other apertures through which the pivot member extends, said apertures being larger than the pivot member so as to afford relative movement between the respective hinge members of the band and support whereby the support may be sustained by the aforesaid lugs and the said bearing parts independently of the hinge connections between the support and band. 80

33. In combination, a burner, a band applied thereto adjacent its upper end, the band having lugs in the vicinity of the front of the burner, a hinge member applied to the band adjacent the rear side of the burner and incorporating lugs, a drum support resting upon said lugs, a drum sustained by the support in operative relation to the burner, a hinge member applied to the drum support, and loose pivotal connection between said hinge members thereby to afford play between said hinge members independent of their pivotal movement. 100

34. In combination, a burner, having bearing parts, a drum support sustained by said parts, a drum surmounting the support and located thereby in operative relation to the burner, loose hinge connections between the drum support and burner, the drum and support being arranged to swing on said hinge connections, and a stop carried by the support for engagement with the burner to limit the swinging movement of the support with respect to the burner. 110

35. In combination, a burner of the character set forth, a drum support surrounding the upper end of the burner and spaced radially therefrom and arranged to tilt with respect thereto, a deflector sustained by said support in operative relation to the top of the burner, and a drum sustained by said support, the drum having air admitting openings outwardly beyond and below the plane of said deflector. 120

36. In combination, a burner of the character set forth, a drum supporting collar surrounding the upper end of the burner and arranged to tilt with respect thereto, 5 the burner and collar having engaging parts through which the collar is supported and properly spaced from the burner, a deflector carried by the collar in operative relation to the top of the burner, and a drum sup- 10 ported by the collar and having air admitting openings outwardly beyond and below the deflector.

37. In combination, a burner of the character set forth, a drum supporting collar 15 hingedly connected thereto, the burner having parts whereby the collar is positioned in proper relation to the burner, a deflector sustained by the collar in operative relation to the top of the burner, and a drum sup- 20 ported by the collar, the drum having air admitting openings outwardly beyond and below the plane of the deflector.

38. A drum for use with burners of the character set forth, said drum comprising a 25 cylindrical shell having a converging annular top wall, a cylindrical inner wall situated within the upper portion of the shell and having a converging top that is spaced from the annular wall of the shell, the lower 30 end of the inner wall being flanged outwardly into contact with the shell whereby it is maintained in properly spaced relation to the shell, the shell having a shoulder whereon the flanged lower end of the 35 inner wall rests, members applied to the upper end of the inner wall and engaging the annular wall of the shell thereby to retain the upper portion of the inner wall centrally within the shell and to hold the inner wall downwardly against the shoulder of the shell, the shell having air admitting 40 openings above the lower end of the inner wall.

39. In combination with a burner of the character described, a drum supporting collar surrounding the upper end of the burner and arranged to tilt with respect thereto, 45 the collar terminating at its upper end in an

outwardly flaring deflector which is spaced a suitable distance from the top of the burner, and a drum having a converging perforated bottom wall, the collar having a ledge whereon said converging wall rests. 50

40. In combination with a burner of the character set forth, an upwardly converging drum supporting collar surrounding the top of the burner and having its upper edge in substantially the plane of, and spaced a suitable distance from, the top of the burner, the collar being arranged to tilt with respect 55 to the burner, a deflector extending upwardly and outwardly from the upper edge of the collar, the collar having a drum supporting ledge substantially midway of its height, a drum having an annular perforated converging bottom wall resting upon the ledge of the collar, and means for holding the drum to the collar during the tilting thereof. 60

41. In a stove structure, a burner of the character set forth, a drum support hingedly connected to the burner, a drum surmounting the support, the drum and support being capable of being tilted to a position wherein they clear the top of the burner 70 allowing access to the flame spreader and wick for the purpose of removing and cleaning the said spreader and wick, and means for sustaining the drum and support in the aforesaid position. 75

42. In a stove structure, a burner of the character set forth, a drum support hingedly connected to the burner, a drum surmounting the support, the drum and support being capable of being tilted to a position wherein they clear the top of the burner allowing access to the flame spreader and wick for the purpose of removing and cleaning the said spreader and wick, and a rest incorporated in the stove structure and so related to the burner as to sustain the drum and drum support in the aforesaid 80 position. 85

In testimony whereof, I hereunto affix my signature.

LEE S. CHADWICK.
